FIG. 1

Patented Sept. 9, 1919.

FIG. 2

FIG. 4

FIG. 3

INVENTOR:

Svante Verner Holm
By Mr. Wallace White

ATTY.

UNITED STATES PATENT OFFICE.

SVANTE VERNER HOLM, OF STOCKHOLM, SWEDEN.

DEVICE FOR THE CARRYING OF CURTAIN-RODS AND THE LIKE.

1,315,553.

Specification of Letters Patent.

Patented Sept. 9, 1919.

Application filed April 3, 1919. Serial No. 287,321.

To all whom it may concern:

Be it known that I, SVANTE VERNER HOLM, subject of the King of Sweden, residing at St. Eriksgatah 16, Stockholm, Sweden, in the Kingdom of Sweden, have invented certain new and useful Improvements in Devices for the Carrying of Curtain-Rods and the like, of which the following is a specification.

10 The present invention has for its object devices for the carrying of curtain rods, drapery poles, and the like. The device is composed of a hook intended to be fastened into sockets or brackets, suitable for the purpose, fixed to a wall, window-frame, or the like, and of members united or connected with the said hook which are intended to fasten around and hold securely the rod in question.

20 In order to make plain the invention, a form thereof is shown, by way of example, on the accompanying drawing, in Figure 1 in lateral view, and in Fig. 2 in front view. Fig. 3 shows in a similar manner to Fig. 1 25 a form furnished with double block pulleys for the running cords, and Fig. 4 a section of the same along the dotted line in Fig. 3.

The invention is described first with reference to Fig. 1. 1 designates the hook, which is intended to be detachably hooked into a fitting or socket 2 fixed in some suitable manner to door frame or window frame, wall, or the like 3.

35 The projecting part 4 of the hook 1 is at its front end furnished with a reduced part 5, so that a shoulder 6 is formed. On the said part 5 is mounted a plate 7 which, together with the plate 8 shaped in a corre-

40 sponding manner, forms a clamp between the upper part of which the curtain rod 9 can be jammed by means of a screw 10, which passes through the plate 8, which latter is adjustably held by the screw, which 45 is screwed into a corresponding threaded boring in the end part 5 of the hook. Between the lower ends of the plates 7, 8 (in cases where a cord-pulling action is to be used) a pulley 11 serving to carry the cords 50 is rotatably arranged. As is known, in self-

drawing curtains of this kind the block at one end of the curtain pole must be provided with two rollers or pulleys. An arrangement of this kind is illustrated in Figs. 3 and 4, which arrangement in other respects 55 resembles that shown in Fig. 1 except that a partition 12 is arranged between the two pulleys and the plates 7, 8, in the manner indicated by Fig. 3, which plates are bent outward in such a manner that they leave 60 room for the pulleys. In order to obviate wear and tear of the cords, the edges 13 of the plates 7, 8 are suitably bent over or rounded in the manner indicated by Fig. 4.

This arrangement makes it possible for the 65 rods in question to be fixed and taken down with the greatest ease.

Having thus described my invention, I declare, that what I claim is:

1. A device for carrying curtain rods and 70 the like comprising a member having a forwardly projecting portion, a shoulder formed on said portion, clamping plates, one adapted to bear against said shoulder, means for holding the other on the end of said portion and exerting a clamping action on said plates, said plates being adapted to clamp 75 a curtain rod.

2. A device for carrying curtain rods and 80 the like comprising a member having a forwardly projecting portion, a shoulder formed on said portion, clamping plates, one adapted to bear against said shoulder, means for holding the other on the end of said portion and exerting a clamping action 85 on said plates, said plates being adapted to clamp a curtain rod above the said member, and a pulley supported by said plates below said member.

3. A device for carrying curtain rods and 90 the like comprising a member having a forwardly projecting portion, a shoulder formed on said portion, clamping plates, one adapted to bear against said shoulder, a screw for holding the other on the end of 95 said portion and exerting a clamping action on said plates, said plates being adapted to clamp a curtain rod.

4. A device for carrying curtain rods and 100 the like comprising a member having a

forwardly projecting portion, a shoulder formed on said portion, clamping plates, one adapted to bear against said shoulder, means for holding the other on the end of said portion and exerting a clamping action on said plates, said plates being adapted to clamp a curtain rod above the said member, and a pulley supported by said plates below said

member, the lower portion of said plates being flanged outwardly from said pulley. 10

In testimony whereof I have affixed my signature in presence of two witnesses.

SVANTE VERNER HOLM.
